UNITED STATES PATENT OFFICE.

MARTIN MOSES, JR., OF NEW YORK, N. Y.

CONTAINER FOR BISCUITS, CRACKERS, AND OTHER COMMODITIES.

1,291,082.

Specification of Letters Patent.

Patented Jan. 14, 1919.

Application filed June 23, 1914, Serial No. 846,735. Renewed June 3, 1918. Serial No. 238,063.

To all whom it may concern:

Be it known that I, MARTIN MOSES, Jr., a citizen of the United States, residing at New York, in the county and State of New York, have invented certain new and useful Improvements in Containers for Biscuits, Crackers, and other Commodities, of which the following is a full, clear, and exact description.

10 This invention relates to boxes or cases suitable for biscuits, "crackers", coffee and other products, and its chief object is to provide a box with a false bottom of improved construction which can be raised 15 from time to time as the goods are removed, thereby keeping the goods always at the top of the box. This makes it easier to remove the remaining goods and displays them to better advantage, as a box having 20 the appearance of being full to the top is more attractive to customers than is one which is nearly empty. A further object is to provide simple but thoroughly effective means for holding the movable bottom 25 in its several elevated positions, and to provide lifting devices of inconspicuous character which will not interfere with the usual flanged closures or lids with which cases for goods of the kind referred to are ordinarily 30 provided. To these and other ends the invention consists in the novel features of construction and combinations of elements hereinafter described.

Upon reading the subjoined description 35 and claims, it will be seen, by those skilled in the art, that the invention can take a number of concrete forms without departure from its spirit, but of these embodiments I have illustrated herein only the 40 one that at the present time is believed to exhibit the invention in its most convenient and effective form. Referring now to the drawings, in which the embodiment mentioned is shown,

45 Figure 1 is a cross section of the box showing the movable or false bottom in its lowermost position and omitting the closure for the box.

Fig. 2 is a view similar to Fig. 1, but 50 showing the movable bottom in one of its higher positions.

Fig. 3 is a perspective view of the movable bottom, with its supports in vertical position.

55 Fig. 4 is a perspective view of one of the

"lifters" by which the movable bottom is raised.

Fig. 5 is a sectional view of the fixed bottom, showing one stage in the manufacture of the preferred form.

60 Fig. 6 is a sectional view showing the box resting on its side, to illustrate the method by which tilting of the movable bottom is prevented under such circumstances.

Fig. 7 is a plan view of the preferred 65 form for the fixed bottom.

Fig. 8 is a detail perspective view showing the hooked lower end of one of the 70 "lifters" in engagement with the movable bottom, and in dotted lines showing it 75 dropped out of engagement with said bottom.

In the particular embodiment illustrated, 80 the sheet metal box 10 is of the usual square or rectangular pattern, and the movable 75 bottom 11 is of such size as to fit the box inside loosely enough to permit the bottom to be raised easily and to leave sufficient space at the sides for the lifters 12. As shown in Figs. 1 and 4, the lifters, made 85 of sheet metal of sufficient stiffness, are formed at the top with outwardly extending hooks to engage the top-edge of the side-walls of the box and at the bottom with inwardly disposed hooks to engage the depending flanges of the movable bottom.

The fixed or permanent bottom of the 90 box is designated by 13 and is provided with a plurality of transverse upwardly extending ribs 14, 15, while the movable bottom 11 is provided on its underside with pivoted legs or supports 16, 17, preferably made of stiff wire bent to the proper form and pivoted to the movable bottom by bending parts of the depending flanges 11^a, 11^b, 95 around them.

When the movable bottom 11 is in its lowest position the legs 16, 17 are folded under it as in Fig. 1. To raise the bottom it is only necessary to draw the lifters 12 upwardly, whereupon the bottoms of the pivoted legs ride over the ribs 14, 15, as pawls over a ratchet. When the bottom is at the desired height the lifters are released and allowed to drop to the positions shown 100 in Fig. 1, and in dotted lines in Fig. 2; but the legs are stopped by the ribs last passed over and hence sustain the movable bottom in a raised position, as in Fig. 2. As the goods (not shown) are removed from 110

the top the operation described is repeated, the movable bottom being thus raised step by step so that the box can always be made to have the appearance of being full or 5 nearly full. When the box is empty the movable bottom can be restored to its initial position by inverting the box so that the pivoted legs will swing down upon the movable bottom, after which the box is allowed 10 to drop down upon the movable bottom. The box can then be turned right side up, leaving the parts in the positions shown in Fig. 1.

The box 10 may be of any suitable size 15 and form, differing from prior types only in respect to its permanent or fixed bottom, which is provided with the transverse ribs 14, 15, already mentioned. Usually the said bottom is of tin or other sheet metal, in which 20 case the ribs can be formed by bending the sheet as indicated in Fig. 5. Instead of having the ribs stand straight up, as in Fig. 5, they may be curved or hooked, as in Figs. 1 and 2, so that if the box is turned on its side, 25 as is often done by the dealer, the legs will be held by the ribs, as in Fig. 6, thereby preventing the legs from swinging downwardly or toward the movable bottom and preventing the movable bottom from falling or tipping forward. For this purpose the ribs 30 are made in three series,—two at the sides and one intermediate, as in Fig. 7. The ribs of the outer series are inclined in one direction, to coöperate with the legs or supports 35 17, and those of the intermediate series are inclined in the opposite direction to coöperate with the support 16.

To insure engagement of the movable bottom by the lifters 12 when the latter are 40 raised, the movable bottom and the lifters may be movably connected, as by guides 19, Fig. 8, which positively guide the lifters into engagement with the flanges 11^a, 11^b, when ever the lifters are drawn up, but permit the 45 lifters to drop to the positions shown in Fig. 1 when they are released.

As previously stated, the invention can be embodied in other forms without departure 50 from its spirit.

50 I claim:

1. A container or box comprising side walls, a fixed bottom, a vertically movable bottom inside the box, supports pivoted at their upper ends to the movable bottom and 55 adapted to be folded under the movable bottom when the latter is in its lowermost position, ribs or stops on the fixed bottom to engage the said supports as the movable bottom is raised to higher positions, and down- 60 wardly extending lifters arranged at the sides of the box and adapted at their lower ends for engagement with the movable bottom to raise the same.

65 2. A container or box comprising side walls, a fixed bottom, a vertically movable

bottom inside the box, supports pivoted at their upper ends to the movable bottom and adapted to be folded under the movable bottom when the latter is in its lowermost position, ribs or stops on the fixed bottom to engage the pivoted supports as the movable bottom is raised to higher positions, and lifters at the sides of the box on the inside, comprising vertical strips formed at their bottoms to releasably engage the movable 75 bottom and at their tops to engage the upper edges of the side walls for suspension therefrom.

3. In a container or box of the kind described, the combination of a vertically movable bottom, means connected therewith to hold the same in raised positions, and a pair of lifters at the sides of the box, having hooked lower ends to engage the movable bottom and be released therefrom by gravity 80 and having their upper ends formed to engage the side walls of the box for suspension therefrom at all positions of the movable bottom.

4. In a container or box of the kind described, the combination of a fixed bottom having oppositely disposed ratchet-ribs, a movable bottom, supports pivoted to the movable bottom and adapted to engage the said ratchet-ribs as the movable bottom is raised to successively higher positions, and means to raise the movable bottom. 90

5. In a container or box of the kind described, the combination of a fixed bottom having at opposite edges two series of ratchet-ribs inclined in the same direction and an intermediate series of ratchet-ribs inclined in the opposite direction, a vertically movable bottom, a pair of supports pivoted at their tops to the movable bottom 100 at the ends of one edge thereof to coöperate with the said two series of ratchet ribs, a support pivoted at its top to the opposite side-edge of the bottom to swing between the other supports and adapted to engage the said intermediate series of ratchet-ribs, and means for raising the movable bottom 110 to successively higher positions.

6. In a container or box of the kind described, in combination, a box having a fixed bottom, a vertically movable bottom inside the box, supports pivoted at their upper ends to opposite sides of the movable bottom and adapted to overlap under said movable bottom when the same is in its lowermost position, manual means to raise the movable bottom, and ratchet ribs on the fixed bottom 115 to engage the lower ends of the said pivoted supports to hold the movable bottom in raised position.

7. In a container or box of the kind described, the combination of a fixed bottom having transverse ratchet-ribs; a vertically movable bottom; a pair of supports pivoted at their upper ends to the movable bottom 120

at the ends of one edge thereof; a support pivoted at its upper end to the movable bottom at the opposite edge to swing between the other supports; said supports overlapping as described when the movable bottom is in its lowermost position and said supports having transverse members at their bottoms to engage successive ribs on the fixed bottom to support the movable bottom 10 at successively higher positions in the con-

tainer or box; and means for raising the movable bottom to such successively higher positions.

In testimony whereof I affix my signature in the presence of two subscribing witnesses.

MARTIN MOSES, JR.
